UNITED STATES PATENT OFFICE.

JOHN PLYM, OF ARGO, ILLINOIS.

ELEVATOR SAFETY APPLIANCE.

1,278,380.

Specification of Letters Patent. Patented Sept. 10, 1918.

Application filed April 23, 1917. Serial No. 163,910.

To all whom it may concern:

Be it known that I, JOHN PLYM, a subject of the King of Sweden, residing at Argo, in the county of Cook and State of Illinois, 5 have invented new and useful Improvements in Elevator Safety Appliances, of which the following is a specification.

This invention relates to devices for automatically stopping and supporting an elevator car or cage in the event of breakage or failure of the usual hoisting cables, and the invention has for its object to provide a novel and improved device of the kind characterized by a catch or brake device 15 which is brought into engagement with the guide or safety rail alongside the car, and which is controlled by the hoisting cables.

In order that the invention may be better understood, reference is had to the accompanying drawings forming a part of this specification and in said drawings—

Figure 1 is a front elevation of an elevator cage or car showing the application of the invention;

25 Fig. 2 is a side elevation thereof;
Fig. 3 is a plan view of a portion of the mechanism; and

Fig. 4 is an enlarged section on the line 4—4 of Fig. 1.

30 Referring specifically to the drawings, 5 denotes the top, 6 the floor, and 7 the sides of an elevator cage or car of conventional construction. The cage is supported by hoisting cables 8 connected to the top there-
35 of and operated in any suitable manner. Two pairs of cables are provided, one pair, as usual, being counterweighted, and the other pair being connected to the hoisting mechanism. As this arrangement is well known, a further description is deemed unnecessary; nor has the hoisting mechanism 40 been shown as it forms no part of the present invention.

On the top 5 of the cage, in proximity to the cables 8, is mounted a series of fulcrum 45 bearings 9 for trip levers 10, one for each cable, one end of the levers being apertured and the cables passing through said apertures. The opposite end of each lever is 50 pressed upward by a heavy expanding coil spring 11. The levers are pivotally mounted to swing in a vertical plane, and when the cables are taut they are held stationary and prevented from being rocked by the 55 springs. The levers are supported by a shaft 10^a carried by the bearings 9.

On the top 5 of the cage are also mounted bearings 12 supporting a rock shaft 13 provided with a series of rocker arms 13^a and a rocker arm 13^b. The rocker arms 13^a 60 rest on that end of the levers 10 which is pressed by the springs 11, and to the rocker arm 13^b is connected a rod 14 which extends downward alongside the car. The rod is also provided with a handle device 14^a for 65 manual actuation, and a turn-buckle 14^b for adjustment and for taking up slack.

The lower end of the rod 14 is connected to a rocker arm 15 on a shaft 15^a supported in a suitable bearing mounted beneath the 70 cage bottom 6. The shaft 15^a has a detent 15^b engageable with a stop tooth 16 on a cam collar 17 fast on a shaft 18 extending transversely beneath the cage bottom. A spring 19 connected to the detent assists to 75 snap the same over the stop tooth.

At both sides of the cage are outstanding horizontally spaced blocks 20 which guide the cage along the web of T-rails 21 mounted vertically in the elevator shaft. 80

On the ends of the shaft 18, are mounted eccentric brake shoes 22 having a toothed or serrated periphery. These brake shoes are positioned opposite the rails 21 to come into frictional engagement therewith when 85 the shaft 18 is rocked. The brake shoes are normally clear of the rails.

In order to rock the shaft 18 to apply the brake shoes 22, said shaft is fitted with outstanding arms 23 which are engaged by 90 coiled springs 24 positioned between said arms and the cage bottom 6. The shaft is locked by the parts 15^b and 16, and the latter, in turn, are controlled by the cables 8 through the parts 10, 13, 13^a, 13^b and 14. 95

It will be understood from the foregoing if the cables 8 should break or fail from any cause, the springs 11 will rock the levers 10, whereupon, through the parts 13, 13^a and 13^b, the rod 14 is drawn upward, and as said 100 rod is connected to the detent 15^b, the latter is tripped off the tooth 16 of the collar 17. The shaft 18 is now released, and the springs 24 rock the same to engage the brake shoes 22 with the rails 21, whereupon the cage is 105 brought to a stop. As each cable 8 is independently connected to a lever 10, the breakage or failure of any one of the cables will bring the safety device into action.

The shaft 18 is supported in bearings 25 110 and slidably mounted on a support 25^a, and engageable by a screw 26, by which latter the

bearing may be adjusted to advance the shaft and thus compensate for wear of the brake shoes 22. The adjusting screw 26 is threaded through a block 27 on the support 25^a.

I claim.

1. The combination with an elevator cage, and a plurality of hoisting cables therefor; of a brake mechanism carried by the cage, 40
10 actuating means for said mechanism, a means for holding the brake mechanism inactive, trip levers carried by the car and having independent connections with the respective cables, means for tilting said levers 45
15 when released by the cables, a rock shaft having rocker arms which are engageable by the trip levers, and a connection between the rock shaft and the aforesaid holding means. 50
2. The combination with an elevator cage, and a plurality of hoisting cables therefor; of a rock shaft carried by the cage, means for actuating said shaft, brake shoes carried by the rock shaft, means for locking 55
20 the rock shaft, trip levers carried by the cage and having independent connections with the respective cables, means for tilting said levers when released by the cables, and a connection between the levers and the 60
25 aforesaid shaft locking means. 65
3. The combination with an elevator cage, and a plurality of hoisting cables therefor; of a rock shaft carried by the cage, means for actuating said shaft, brake shoes carried by the rock shaft, means for locking the

rock shaft, trip levers carried by the cage and having independent connections with the respective cables, means for tilting said levers when released by the cables, a rock shaft having rocker arms which are engageable by the trip levers, and a connection between the last mentioned rock shaft and the aforesaid shaft locking means.

4. The combination with an elevator cage, and the hoisting cable thereof; of a brake mechanism carried by the cage, means for holding the brake mechanism inactive, a trip lever carried by the cage and having a connection with the cable, means for tilting the lever when released by the cable, a rock shaft having a rocker arm which is engageable by the trip lever, and a connection between the last mentioned rock shaft and the aforesaid holding means.

5. The combination with an elevator cage, and the hoisting cable thereof; of a rock shaft carried by the cage, means for actuating said shaft, a brake shoe carried by the rock shaft, means for locking said shaft, a trip lever carried by the cage and having a connection with the hoisting cable, means for tilting said lever when released by the cable, a rock shaft having a rocker arm which is engageable by the trip lever, and a connection between the last mentioned rock shaft and the aforesaid shaft locking means.

In testimony whereof I affix my signature.

JOHN PLYM.
